UNITED STATES PATENT OFFICE.

JAMES SWEENEY, OF MOUNT STERLING, ILLINOIS.

TRACTION-WHEEL.

No. 836,225.

Specification of Letters Patent.

Patented Nov. 20, 1906.

Application filed March 9, 1906. Serial No. 305,078.

To all whom it may concern:

Be it known that I, JAMES SWEENEY, a citizen of the United States of America, residing at Mount Sterling, in the county of 5 Brown and State of Illinois, have invented certain new and useful Improvements in Traction-Wheels, of which the following is a specification.

This invention relates to new and useful 10 improvements in traction-wheels, and has for its object to provide a novel device of this character that can be used in combination with wheels of ordinary construction in order that the said wheels may easily travel over 15 soft beds or in case of an unusually heavy load and prevent the same from sinking within the roadway.

It is also an object of this invention to provide a traction-truck wherein the wheels of 20 the truck may be adjusted laterally one with relation to the other.

It is also the object of the invention to provide a novel device of this character that is readily applied and removed from the ordinary 25 wheels.

Finally, an object of this invention is to produce a device of the character noted possessing advantages in points of efficiency, 30 simplicity, and durability, proving at the same time comparatively inexpensive to produce and maintain.

With the foregoing and other objects in view the invention consists in the details of construction and in the arrangement and 35 combination of parts to be hereinafter more fully set forth and claimed.

In describing the invention in detail reference will be had to the accompanying drawings, forming part of this specification, 40 wherein like characters denote corresponding parts in the several views, in which—

Figure 1 is a top plan view of the truck with the traction-wheels applied thereto. Fig. 2 is a view in elevation of a truck, the ordinary wheel being shown in dotted lines. 45 Fig. 3 is a view in elevation with the plate removed. Fig. 4 is a sectional view taken centrally of Fig. 2.

In the drawings, 1 denotes an axle of a 50 truck, the ends of which are screw-threaded. Loosely mounted on the threaded portions of the axle are supporting-wheels 3, which may be of any ordinary or preferred construction.

The traction-wheel proper comprises a metallic case 5, which has its faces 6 open except 55 for the annular flanges 7. These flanges are provided with a series of apertures 8.

The traction-wheel is of greater diameter than the supporting-wheel proper, said supporting-wheel being insertible within the 60 traction-wheel through one of the openings 6.

The openings are provided with the covers 15, which are provided with a series of openings adapted to register with the openings 8 of the flanges 7. Through these openings 65 pass headed screws 16, the heads thereof being within the case or traction-wheel and bearing against the interior face of the flange. Nuts 17 engage the threaded portions of the bolts and bind against the exterior of the 70 covers 15 and hold the same against the flanges 7. Thus it can be seen that the covers 15 can be easily removed for the purpose of applying the wheel 3 within the case of the traction-wheel or withdrawing it from 75 the same. The covers 15 are provided with alining central openings 9, surrounded with outturned annular flanges 10. Engaging the flanges 10 are the caps 11 and 12. These 80 caps are not secured to the flanges, but permit the flanges to rotate therein. The shaft 1 passes eccentrically through these caps and said caps are held immovable on the shaft by means of the nuts 13 14 and 21 22, respectively, threaded on the axle and positioned 85 on the opposite sides of the caps and binding thereagainst. In the drawings the locking or binding nut 23 is provided for the nut 21.

In operation the wheel 3 being loose within the traction-wheel and the traction-wheel being so mounted that a portion of the wheel contacts therewith, hence as the wheel 3 advances it will contact with the traction-wheel and cause it to rotate within the caps 11 and 12, and as the tread of the traction-wheel is greatly in excess of the tread of the 95 wheel proper it will be readily understood how its function is performed.

In order to laterally adjust the traction-wheel or the wheel proper, it is but necessary 100 to loosen the nuts on the shaft, it being understood that turning the nuts in one direction will lengthen the distance of the wheels one from the other and turning the nuts in an opposite direction will shorten the distance 105 or space.

Having fully described my invention, what I claim as new, and desire to secure by Letters Patent, is—

1. In combination, with a supporting-wheel and its axle, a traction-wheel embracing the supporting-wheel and mounted on the axle eccentrically with relation to the supporting-wheel.
2. In combination with an axle, supporting-wheels thereon, a traction-wheel inclosing said supporting-wheels, each of the traction-wheels having annular flanges on their opposite faces and caps carried by the axle and engaging the flanges of the traction-wheel, said traction-wheel being free to revolve within the caps of the axles.
3. In combination, a supporting-wheel, a traction-wheel embracing the supporting-

wheel and mounted eccentrically with relation thereto, said traction-wheel comprising a hollow casing having one of its faces open for the insertion of the supporting-wheel and a cap for closing said opening.

4. In combination with an axle and a wheel loosely mounted thereon, a traction-wheel embracing the supporting-wheel and mounted on the axle eccentrically, and means for adjusting the traction-wheel longitudinally of the axle.

In testimony whereof I affix my signature, in the presence of two witnesses, this 7th day of March, 1906.

JAMES SWEENEY.
